DECORTICATOR FOR HULLING GRAINS

Edgard Grimard, Liege, Belgium

Application April 23, 1952, Serial No. 283,858

Claims priority, application Belgium April 27, 1951

1 Claim. (Cl. 146—290)

This invention relates to decorticators for hulling grains of corn or other cereals, the apparatus being of the type comprising a vertical cylindrical vessel in which there revolves a vertical shaft carrying rubbing members, which may be separated by fixed baffles.

An object of the present invention is to subject the grains, when under treatment, to continuous rubbing and rolling motions during the rotation of the vertical shaft. Another object is to improve the distribution and the hulling of the grains. Other objects will hereinafter appear.

According to the invention, a rotor element carrying the rubbing members (if desired in a detachable and interchangeable manner) is constituted by a hub fixed upon the shaft, provided at its periphery and at different levels with sets of arms extending in radial directions, either perpendicularly or in an inclined relation to the vertical axis of the shaft, alternate arms being provided with rubbing members in the form of vertical cylindrical pegs and with rubbing members in the form of vertical blades or vanes inclined at an angle to the radius of the respective arm.

The improved apparatus may comprise any number of rotor elements of conical aspect, having the arms extending in inclined relation to the axis, with at least one flat rotor element, having the arms extending perpendicularly to the axis, this flat element facing an opening for discharge of the material, or it may comprise only flat rotor elements, mounted upon the central shaft.

After the introduction into the apparatus of the grains which have been subjected to a suitable degree of humidification with a view to the operation of hulling or stripping the pericarp, there will thus be obtained a rubbing and rolling of the grains over and in relation to one another, due to the particular form of the rotor elements and rubbing members, which brings about in a perfect manner the stripping of the pericarp from the grain properly so-called, which is the result envisaged.

Decorticating apparatus provided with the improved rotor elements can be constructed in different ways and there will be described in the course of the present specification by way of example two embodiments of the decorticating, after having described the rotor elements which form the characteristic features thereof.

The invention is hereinafter described with reference to the accompanying drawings which represent by way of explanation and not of limitation, the improved decorticating elements and two forms of apparatus embodying such elements; in these drawings,

Fig. 1 is an elevation of a rotor element of conical aspect with its arms inclined in relation to the horizontal and to the vertical axis.

Fig. 2 represents in elevation the development of the central hub of the rotor element represented in Fig. 1 showing the angular relation of the arms at the periphery of the hub.

Fig. 3 is a view analogous with Fig. 1, but showing a flat rotor element, with its arms inclined to the horizontal but perpendicular to the axis.

2

Fig. 4 is a view analogous with Fig. 2, but illustrating by way of example an arrangement of the hub for exclusively horizontal arms.

Fig. 5 is a plan view of Fig. 3.

Fig. 6 represents an elevation partially in section of a decorticating embodying three rotor elements of conical aspect and one flat rotor element.

Fig. 7 represents an elevation partially in section of another form of decorticating embodying only three flat elements.

Referring to Fig. 1 which represents a rotor element of conical aspect, 1 represents a central hub or sleeve intended to be fixed upon a vertical rotary shaft, for example by pins or set screws 5. A number of radial arms 2 in the form of flat bars are fixed at an angle and at two different levels upon the hub or sleeve 1, see Fig. 2; each arm extends out from the hub 1 in a radial sense but is inclined in relation to the vertical axis of the hub 1. Some of the arms 2, for example three out of six, are provided with vertical, cylindrical pegs passing transversely through them to act as combs or strippers; these pegs may be all of equal height on either side of the arm 2, like the pegs 4, or they may be fixed at different heights in relation to the inclined plane of the corresponding arm, like the pegs 6 and 7. These pegs 4, 6 and 7 are in alignment one behind another along the respective arm and spaced apart at equal distances. Other arms 2 alternating with the arms carrying the cylindrical pegs 4, 6 and 7, are preferably set at the lower of the two levels upon the hub 1, as best seen in Fig. 2; these arms are provided with flat blades or vanes 3 disposed vertically, these blades being aligned parallel to one another and spaced apart at equal distances but inclined at an angle (see Fig. 5) in relation to the radius of the respective arm.

In Fig. 3, the central hub 1a carries arms 2a in the form of flat bars disposed at two different levels upon the hub or sleeve 1a, but extending perpendicularly to the axis, contrary to the arms in Fig. 1; these arms 2a may be inclined, like those of Figs. 1 and 2, or set perpendicular to the axis, for example as in Fig. 4.

It will be noted that in all cases an arm 2 or 2a carrying pegs 4, 6 or 7, will alternate in circumferential direction with an arm 2 or 2a carrying blades or vanes 3, as clearly seen in Fig. 5; any number of hubs 1 and/or 1a may be fixed upon a central driving shaft the hubs being staggered in relation to one another in the circumferential direction.

Fig. 6 represents one example of my improved decorticating formed by an upright vessel 12, provided with one solid end or base 17 and a removable lid 15 having openings 16 for the introduction of the grain material, a number of external bolts 13 with locking nuts 14 fixing the assembly in a quite rigid manner. A vertical shaft 9 revolves in a ball-bearing journal 10 mounted in the lid 15, and its lower extremity revolves in a footstep bearing 11 in the bottom end or base 17.

Inside the vessel 12 there is shown a funnel 27 fixed in position by means of gussets 34, its central opening 28 distributing the material poured in through the opening 16, in the direction of the arrows on to the rotor element of conical aspect formed by the topmost hub 1 and the inclined arms 2 carried thereby.

The vertical shaft 9 is provided with a series of these rotor elements of conical aspect, such as represented in Figs. 1 and 2; at the bottom there is a flat element such as represented for example in Figs. 3 and 5, but preferably having its arms 2a set flat as in Fig. 4. The arms 2 secured to each hub 1 are shown projecting at different levels.

The hubs 1 are shown separated from one another by fixed frusto-conical baffles each comprising for example a frusto-conical wall 29 forming a collector, its outer periphery having one or more gaps or other passages 30 for the

discharge of the material on to a lower frusto-conical wall 31, which brings back the material towards the center, where it falls again through an opening 32 on to the next hub 1 carrying inclined elements, this outward and inward travel of the material being repeated on the following stages.

The baffle walls 29 and 31 may be connected together by distance pieces 33, as shown, but this is not indispensable; the said walls 29 and 31 can be fixed separately in the interior of the vessel 12 by means of gussets such as 34.

It is to be noted that the baffles 29 and 31 may be omitted in the case where the vessel 12 is intended to be filled with grains; the latter will then not be compelled to travel along the alternately outward and inward path indicated by the arrows represented along the baffle walls 29 and 31.

In the wall near the bottom of the vessel 12 there is arranged a tangential opening 19 regulated by a register 19a of arcuate shape, controlled from the exterior, in order to regulate the delivery into the discharge conduit 18; upon the latter there is connected the intake of a conduit for sucking off the husks or pericarps of the dehulled grains, while the latter are conveyed by gravity to their eventual destination.

The arms such as 2 and 2a in each rotor element of the apparatus may with advantage be six in number, as shown in Fig. 5, but the invention is not limited to any specific number of arms, nor to the number of rotor elements of conical aspect and flat rotor elements, Figs. 1 and 2 respectively, to be utilized in the decorticator.

The operation of the decorticator will be easily understood from Fig. 6, the arrangement of the rotor elements causing the grains during the rotation of the shaft 9 to be continually combed, rubbed and rolled over one another and in relation to one another, whereby there is obtained a high-quality product; the apparatus may be employed for treating grain of any nature or origin.

Fig. 7 illustrates another embodiment of the invention, utilizing the same external arrangement as in Fig. 6, but with certain internal differences; first, the central vertical shaft 20 revolves in an upper bearing 21 supported by the lid 15 which is provided with openings 16, and it rests in a footstep bearing 22 upon a base 26, the shaft being driven through bevel gear-wheels by a shaft 24. Secondly, the rotor elements used are all of the flat type represented in Figs. 3 and 5, and are spaced at a distance from one another by sleeves 25, for example. The radial arms of each of these rotor elements are set at different heights upon the hub or sleeve 1a pinned to vertical shaft 20. In this apparatus no baffles are provided and it is loaded or filled with grains during operation, the supply through the fun-

nel 27 and its central opening 28 being regulated in suitable relation to the discharge which takes place at 18 as above described.

It will be noted that by the comb-like constructions of the rotor elements with pegs or projections from the radial arms, a very effective stripping action is obtained.

It is obvious that other forms of embodiment of the decorticator may be contemplated, comprising a combination of rotor elements like those represented in Figs. 6 and 7; as already pointed out, these embodiments are described by way of explanation of applications of the invention, without excluding the possibility of construction of other forms, for example like that of Fig. 6 but without the baffles 29 and 31.

What I claim is:

A decorticator for hulling humidified grain including a vessel having a vertical cylindrical wall and an inlet and outlet at the top and bottom, respectively of the vessel, a vertical shaft mounted to revolve in said vessel and having a plurality of rotor elements each comprising a hub and two groups of arms extending radially therefrom in alternate positions and inclined upwardly with respect to the axis of rotation of the shaft, said rotor elements being spaced from each other on said shaft, a series of frusto-conical baffles arranged in pairs between successive rotor elements and secured within said vessel at vertically spaced locations to define an annular space between each pair of baffles, the upper one of each of said pairs of baffles having discharge passages adjacent the outer periphery thereof, and the lower baffle of each pair, at its inside edge, defining a central opening around said shaft, and a lowermost rotor element on said shaft comprising arms disposed perpendicularly to the shaft, whereby grain supplied to said vessel through said inlet is moved radially outward and upwardly by each of said plurality of rotor elements in turn over the upper one of the underlying pair of baffles to fall through said discharge passages into said annular space where the grain moves, by gravity, radially inward and downwardly to fall through said central opening for operation thereon by the next lower one of said plurality of rotor elements.
